UNITED STATES PATENT OFFICE

116,646

DESIGN FOR A HEAD COVERING OR SIMILAR ARTICLE

John Rannells, New York, N. Y.

Application January 30, 1939, Serial No. 82,657

Term of patent 3½ years

To all whom it may concern:

Be it known that John Rannells, a citizen of the United States, residing at 71 West Eighty-eighth Street, in the Borough of Manhattan, city, county, and State of New York, has invented a new, original, and ornamental Design for a Head Covering or Similar Article, of which the following is a specification, reference being had to the accompanying drawing, forming a part thereof, wherein;

Fig. 1 is a top plan view of a head covering embodying my design; and

Fig. 2 is a perspective side view thereof.

I claim:

The ornamental design for a head covering or similar article, as shown.

JOHN RANNELLS.
